Primary Examiner — Katie Jane Stofko*(74) Attorney, Agent, or Firm* — Faegre Drinker Biddle & Reath LLP(57) **CLAIM**

The ornamental design for an amplifier for automobile, as shown and described.

DESCRIPTION

FIG. 1 is a perspective view of an amplifier for automobile showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken line showing of the amplifier for automobile is included for the purpose of illustrating portions of the amplifier for automobile and forms no part of the claimed design.

1 Claim, 7 Drawing Sheets(56)
